FIG. 3

FIG. 5

FIG. 1 is a perspective view of a basket for flowers or the like embodying my new design;

FIG. 2 is a fragmentary medial sectional view on an enlarged scale taken on a vertical plane passing through line 2-2 of FIG. 1;

FIG. 3 is a front elevational view looking in the direction of the arrows 3-3 of FIG. 1;

FIG. 4 is a bottom plan view on the same scale as FIG. 1 looking in the direction of the arrows 4-4 of FIG. 2; and

FIG. 5 is a fragmentary vertical sectional view taken along line 5-5 of FIG. 2.

The woven material appearance of the surface ornamentation is continuous over the entire bottom and top surfaces of the basket.

I claim:
The ornamental design for a basket for flowers or the like, as shown and described.
